DESIGN FOR A DISPLAY BOX FOR JEWELRY

George B. Nathanson, Brookline, Mass.

Application September 18, 1935, Serial No. 58,617

Term of patent 7 years

To whom it may concern:

Be it known that I, George B. Nathanson, a citizen of the United States of America, residing at Brookline, in the county of Norfolk and Commonwealth of Massachusetts, have invented a new, original, and ornamental Design for a Display Box for Jewelry, of which the following is a specification, reference being had to the accompanying drawing, forming part thereof.

The figure is a perspective view of the display box for jewelry showing my design. The box as shown has a flat central-supporting section surrounded by a raised molding, which in turn is surrounded by a flat spacing surface below the level of the molding. The spacing surface is surrounded by a raised edge or molding forming a continuation of the sides of the box. The central molding and the molding formed by the extensions of the sides of the box are in contrasting colors to the central supporting surface and the spacing surface, as indicated by the shading in the drawing.

I claim:

The ornamental design for a display box for jewelry as shown and described.

GEORGE B. NATHANSON.
